BUCKLE FRAME

Joseph J. Schutz, New Haven, Conn., assignor to
Parva Products Company, Chicago, Ill., a cor-
poration of Delaware

Application March 11, 1948, Serial No. 145,040

Term of patent 7 years

(Cl. D17—1)

To all whom it may concern:

Be it known that I, Joseph J. Schutz, a citizen of the United States, residing at New Haven, in the county of New Haven and State of Connecticut, have invented a new, original, and ornamental Design for a Buckle Frame, of which the following is a specification, reference being had to the accompanying drawing, forming a part thereof.

Fig. 1 is a top plan view of a buckle frame, embodying my new design;

Fig. 2 is a side elevational view of the buckle frame shown in Fig. 1;

Fig. 3 is a front end view thereof; and

Fig. 4 is a perspective view of the buckle frame shown in Figs. 1 to 3.

I claim:

The ornamental design for a buckle frame, sub-
stantially as shown.

JOSEPH J. SCHUTZ.
